CHARLES SCHAER, OF LANGENTHAL, SWITZERLAND, ASSIGNOR TO THE FIRM SULZER
FRERES SOCIETE ANONYME, OF WINTERTHUR, SWITZERLAND

HIGH-PRESSURE PISTON OR RECIPROCATING COMPRESSOR

Application filed February 16, 1928, Serial No. 254,728, and in Switzerland October 8, 1927.

This invention relates to high pressure piston or reciprocating compressors or the like of the kind in which the driving apparatus drives the compressor piston or intermediate 5 piston connected thereto through the medium of an oscillating column of liquid.

According to the present invention each liquid column is provided with at least one automatically opening closure member. The 10 closure member may constitute a relief valve for the escape of air from the liquid column, or a safety device which opens when a maximum permissible pressure is exceeded. When at least two liquid columns and more 15 than one valve or closure member are provided, the liquid columns may be connected together by valves by means of which the pressure difference can again be correctly adjusted automatically when excessive differences in pressure occur between the liquid 20 columns. Preferably each liquid column is not only provided with at least one closure member in the form of a relief valve, but also with at least one closure member in the form 25 of a safety device. In addition at least one of the closure members may serve as a feed device for the liquid column.

The invention is particularly applicable to compressors of the above type in which the 30 intermediate piston, i. e. the piston which drives the compressor piston, is exposed on both faces to the said column.

A few constructional examples of the invention in its application to a high pressure 35 reciprocating compressor are illustrated by way of example in the accompanying drawings, in which

Figure 1 shows a compressor according to the invention partly in section, and partly in 40 elevation,

Figures 2, 3 and 4 show modified forms of compressor according to the invention, and Figure 5 shows a detail.

In the construction illustrated in Figure 1 45 the primary piston 2 of the driving machine (not shown) reciprocates within a cylinder 1 while the intermediate pistons 5 and 6 reciprocate within cylinders 3 and 4 respectively and actuate the compressor pistons 7 and 8. On the casings 9 and 10 are mounted

the compressor cylinders A and B. In the cylinder spaces to the left and right of the piston 2 are disposed the driving liquid columns I and II, whilst in the connecting member 11 is enclosed a connecting liquid column 55 III. Oil is preferably used as the pressure transmitting medium and this is supplied to the columns III, I and II by the feed devices 15, 16 and 17 respectively. Each of the 60 chambers, containing the liquid columns III, I and II is provided with a closure member in the form of a safety device 12, 13 and 14 respectively and with at least one closure member in the form of an air relief valve 18, 18¹ or 19 or 20. The safety devices may, for example, be in the form of outlet valves of known construction and may terminate in a collecting pipe or a collecting tank not shown. The feed devices are connected to a pressure supply pipe, or to a pressure supply tank not 70 shown. In addition to the above mentioned devices the piston 2 of the driving machine is provided with valves 21 and 22 and the pistons 5 and 6 with valves 23, 24 and 25, 26 respectively. For the sake of clearness the 75 valves, which are spring controlled, are shown as open in the mid position of the piston, whilst in the dotted end positions of the piston they are shown in the position which they then occupy.

The displacement volume (stroke $\times$ piston area) of the primary piston 2 of the driving machine is larger than the displacement volumes of the intermediate pistons 5 and 6 at the least by the amount of oil losses. The 85 stroke of the piston 2 is limited by the size of the crank of the driving machine, not shown, whilst the stroke of the pistons 5 and 6 is limited by stops 40 and 41 and 42 and 43 respectively. As a result, the intermediate 90 pistons will reach the limits of their strokes before the primary piston 2 has reached its end position. Excessively high pressures would therefore occur in the oil columns if 95 means were not provided for controlling these pressures. According to Figure 1 this is effected by providing in each piston 2, 5 and 6 two valves 21, 22 and 23, 24 and 25, 26 as described above, and so constructing these valves that when the pressure on one face 100

of the piston exceeds that on the other face by a predetermined amount, oil can pass through. If now the piston 5 reaches the end of its stroke before the piston 2 has reached the end of its stroke, i. e. while it is still moving to the left, the oil, which the latter piston continues to displace until it reaches its left hand reversing point passes through the valve 23 into the liquid column III, thus relieving the excess pressure. Should the piston 6 have already reached the upper end of its stroke oil will flow from the chamber III through the valve 26 into the liquid column II. The oil which has been lost during the operation by leakages is replaced through the feed valves 15, 16 and 17. If, for example, liquid has been lost from the column I through the stuffing boxes, the piston 5 will reach the stop 40 limiting the upward stroke before the piston 2 has reached the end of its stroke to the right. A vacuum would therefore be produced on the left-hand side of the piston 2 in the liquid column I if the oil were not automatically replaced through the valve 16 which, during a predetermined portion of the stroke has a higher pressure than the liquid column itself. The replacement of oil in the oil columns II and III is effected in a similar manner.

If an extremely rapid adjustment is required to avoid large increases in pressure, closure members 12, 13 and 14 in the form of safety valves, are provided. The valves 21 to 26 are not absolutely essential as their purpose can be fulfilled by the safety devices 12, 13 and 14.

The construction shown in Figure 2 differs from that shown in Figure 1 in that two feed valves 15 are provided for the connecting liquid column III. One of these, for example, the left-hand one, supplies pressure transmitting liquid of normal pressure when the device is inoperative, while the right-hand one supplies liquid at increased pressure. The piston 2 of the driving machine and the intermediate pistons 5 and 6 are not provided with valves in this construction. In place thereof there is provided an automatically opening closure member which acts as a by-pass device. The liquid column I is connected by the valve 27 and the by-pass pipe 28 to the coupling liquid column III, whilst the liquid column II is connected to the liquid column III by the valve 29 and the by-pass pipe 30.

In accordance with the method of construction adopted, the displacement volume of the piston 2 is larger than that of the pistons 5 and 6; the latter therefore reach the limits of their strokes before the piston 2 has reached its dead point positions. If an excess pressure now occurs, for example in the column I relatively to the column III, this pressure will be adjusted by a corresponding discharge through the overflow

valve 27 which is adjusted according to the conditions of working. If a predetermined, maximum permissible pressure is exceeded in one of the columns I, II and III then an equalization is effected through the safety devices 12, 13 and 14 which then open. The oil which has passed out and is lost by reason of leakages is replenished by the replenishing valves 16 and 17, for example from the lubrication conduits. The by-pass devices may be replaced by a suitable construction of the safety devices 12, 13, 14.

Figure 3 shows an application to a compressor in which the connecting liquid column is located above the piston 2 of the driving machine and in this case separate by-pass members, or piston valves of equivalent action are not provided. For the purpose of replenishing all three columns, feed valves 15, 16 and 17 are, however, provided and in addition to the closure members 18, 18¹, 19 and 20, formed as air escape valves, there are provided safety valves 12, 13 and 14 which open when a maximum permissible pressure is exceeded. If during the operation too much oil is present in any column for any reason, it can flow out through the safety valves, also a deficiency in oil is immediately made up when the pressure in one of the columns has been reduced to a value below that of the replenishing oil.

In order to avoid shocks or knocking, the intermediate pistons 5 and 6 may also be provided with extensions 44 and 45 which in the neighbourhood of the dead point engage with a stop, such for example as 43 or 40, to limit their stroke, in such a manner that the liquid displaced by the pistons is throttled. In this manner the movement of the pistons 5 and 6 is retarded towards the end of the stroke and they come into contact with an oil cushion 47 as is indicated by dotted lines in the case of the driving piston 6 shown in Figure 5.

In the single stage compressor illustrated in Figure 4, two feed valves 31 and 32, and two equalizing valves 36 and 37 are provided for adjusting the pressure in the liquid columns, an air relief valve 38 being provided for the liquid column I. Similarly the column II has two air relief valves 39 and 46 and each column has a safety valve 33 and 34. These only come into operation when the pressure in the liquid columns exceeds a predetermined amount, for example should the valves 36 and 37 fail. The method of operation corresponds with that of the piston machines previously described. If desired, the air relief valve may be connected to a safety device.

I claim:

1. In a high pressure reciprocating compressor, the combination with a primary piston effecting a positive movement, of at least one intermediate piston, a compressor piston

connected to said intermediate piston, an oscillating column of liquid between said primary and intermediate pistons, means for supplying liquid to said liquid column, and 5 means for allowing the escape of air from said liquid column.

2. In a high pressure reciprocating compressor, the combination with a horizontally arranged primary piston effecting a positive 10 movement, of a plurality of vertically arranged intermediate pistons, a compressor piston connected to each intermediate piston, an oscillating column of liquid between one side of said primary piston and one of said intermediate pistons, a second oscillating liquid column between the other side of said primary piston and another of said intermediate pistons, a third oscillating column of liquid between said intermediate pistons, 15 means for supplying liquid to said liquid columns, and a relief valve for the escape of air from each of said liquid columns.

3. In a high pressure reciprocating compressor the combination with a primary piston effecting a positive movement, of at least 20 one intermediate piston, a compressor piston connected to said intermediate piston, an oscillating column of liquid between said primary and intermediate pistons, means for 25 supplying liquid to said liquid column, a relief valve for the escape of air from said liquid column, and a safety device which opens when a maximum permissible pressure in said liquid column is exceeded.

35 4. In a high pressure reciprocating compressor the combination with a horizontally arranged primary piston effecting a positive movement, of a plurality of vertically arranged intermediate pistons, a compressor 40 piston connected to each intermediate piston, an oscillating column of liquid between one side of said primary piston and one of said intermediate pistons, a second oscillating liquid column between the other side of said 45 primary piston and another of said intermediate pistons, a third oscillating column of liquid between said intermediate pistons, means for supplying liquid to said liquid columns, a relief valve for the escape of air 50 from each of said liquid columns, and a safety device which opens when a maximum permissible pressure in said liquid columns is exceeded.

55 In testimony whereof I have affixed my signature.

CHARLES SCHAER.
